UNITED STATES PATENT OFFICE.

JOHN T. FOSTER, OF ARLINGTON, NEW JERSEY.

DISHCLOTH-HOLDER.

SPECIFICATION forming part of Letters Patent No. 296,550, dated April 8, 1884.

Application filed December 21, 1883. (No model.)

To all whom it may concern:

Be it known that I, JOHN T. FOSTER, of Arlington, Hudson county, New Jersey, have invented certain new and useful Improvements in Dishcloth-Holders, of which the following is a specification.

My invention relates to that class of tongs or clasps adapted to grasp and hold a dishcloth and enable the same to be used in hot water to clean deep or flat dishes without the necessity of bringing the hand in contact with the cloth, the interior of the dish, or with the hot water. Such devices generally consist of a long stem or handle having two divergent 15 grasping-jaws on one end and a sliding manipulating device on the stem, whereby the jaws may be closed or opened to grasp or release the cloth. My improvements lie in the special construction of the grasping-jaws and 20 of the sliding manipulating device in the stem and in the operating connection between the two, as hereinafter fully set forth, whereby a very efficient utensil is produced.

In the drawings annexed, Figure 1 presents 25 a side elevation of my improved utensil shown partly in section, and Fig. 2 shows a front elevation of the same.

In these views, *a* indicates the stem of the utensil, which is of a length suitable to reach 30 into dishes, and is preferably made of a light round metallic rod. On one end of this rod *a* is fixed a wooden or other handle, *b*, and at the opposite end two grasping-jaws, *c c*, are pivoted thereto on a rivet, *d*. These jaws are 35 preferably formed and arranged relatively to each other like the two halves of a bivalve shell, and, being hinged by the rivet *d* to the end of the rod *a*, are thus capable of opening apart and closing together, as shown by full 40 and dotted lines in Fig. 1. I prefer to form these shell-like jaws in shape similar to a scallop shell with radial corrugations, as shown in Fig. 2, the scalloped edges of the jaws being, however, exaggerated, so as to form blunt 45 but distinct teeth *c*, which are coincident with said corrugations, and will intermesh when the jaws close together, as shown in Figs. 1 and 2, and thus hold more firmly anything placed between the jaws. This form of the 50 jaws is therefore not only pleasing and attractive, but is a shape well adapted to be

struck up from thin sheet metal and yet render the jaws very strong and stiff, and adapted to take a very firm hold on anything which they may grasp. Now, on the rod *a*, near the 55 handle *b*, is fitted a sliding manipulating knob or sleeve, *f*, having laterally-projecting cross-bar or wings *f'*, adapted to the grasp of the fingers, and on each side of this sleeve a light rod or tongue, *g*, is fixed, and extends from 60 thence nearly parallel with the rod *a* toward the jaws, being bowed outward near the jaws, with their extremities hooked and passed into slots *i i* in the back of the jaws and engaged with a bar, *k*, between said slots, as fully shown 65 in Figs. 1 and 2. The tongues *g g* therefore form an operative connection between the sleeve *f* and the jaws, and these tongues are preferably strong springs having a constant tendency to spring toward each other and 70 firmly close the jaws, as shown by full lines in Fig. 1; and it will be seen that as the tongues connect with the jaws at a lateral distance from their pivot *d*, and as the sleeve is free to move on the stem *a* toward the handle, hence 75 if the sleeve is slid in this direction the tongues will pull open the jaws, and this opening motion will further flex and diverge the springs, as indicated by dotted lines, whereas, when the sleeve is released, the reaction of the 80 springs will immediately close the jaws together and forcibly grasp any cloth or other article placed between, as will be readily comprehended. In using the device, therefore, the manipulating end of the device is grasped in 85 the hand, with the end of the handle *b* resting against the thumb or against the palm of the hand, while the first and second fingers straddle the stem and rest upon the wings *f'*. By now exerting the pressure of the fingers on the 90 said wings *f'*, the sleeve will be slid toward the handle until stopped by the ferrule of the handle, which thus limits the movement of the sleeve, and this movement will diverge or open the jaws, as indicated by dotted lines in 95 Fig. 1, thus enabling the dishcloth or other article to be placed within the grasp of the jaws, and as soon as the pressure of the fingers is relaxed the sleeve will spring back to its normal position, and the jaws will be closed 100 firmly together on the cloth by the action of the springs *g g*, as will be readily understood,

and this grasp will continue without any effort of the hand, or without the necessity of any locking device, so long as the sleeve remains in its normal position. This device 5 will therefore enable the cloth to be used to wash deep or shallow dishes, and to be used in very hot water, or on greasy dishes, without requiring the contact of the hands therewith, which will therefore render the washing 10 operation not only much more pleasant, but enable it to be done quicker and much more perfectly on account of the greater reach thus obtained, and the fact that much hotter water can be used than would be possible with 15 the hand in contact therewith.

It will be seen that instead of having both jaws movable with the two operating tongues, *g g*, one jaw may be fixed, and the other movable, with one tongue connecting therewith. 20 I, however prefer the duplex construction shown. It will also be noted that in the construction I illustrate the tongues *g* serve both as closing-springs and operating-rods, between the sleeve and jaws. If desired, however, the tongues may be rigid to serve simply 25 as connecting-rods, while a separate spring or springs may be used to close the jaws; but it is obvious that the preferred construction is much simpler and presents an advantage which 30 forms one feature of my invention.

What I claim is—

1. A grasping-tongs for holding dishcloths or other articles, consisting of a stem or handle, two grasping-jaws on the end thereof, 35 a spring tongue or tongues arranged to constantly hold the said jaws closed by lateral pressure thereon, and a longitudinally-sliding manipulating device for flexing said tongues, and thus opening the jaws, substantially as 40 herein set forth.

2. A device for holding dishcloths, &c., consisting of a stem, *a*, having a suitable handle, in combination with the jaws *c c*, hinged

on the end of the stem and formed of sheet metal shaped and corrugated in the form of 45 scalloped shells, with suitable means for opening and closing said shells, substantially as herein set forth.

3. The combination, with the stem *a* and handle *b*, of the hinged jaws *c c*, formed in the 50 shape of corrugated shells, with toothed intermeshing edges, and with suitable means for opening and closing said jaws, substantially as herein set forth.

4. The combination, with the stem *a*, having a suitable handle, of jaws *c c*, hinged on the end thereof, a manipulating sleeve or knob sliding on said stem, and one or more tongues or rods, *g g*, connecting said sleeve with one or both of said jaws, substantially as and for the 55 purpose set forth.

5. In a device for holding cloths, &c., the combination, with a handle and grasping-jaws supported therefrom, of a sliding manipulating sleeve or knob operatively connected with the jaws to open the same, and formed with the laterally-projecting finger-rests *f' f'*, substantially as and for the purpose 60 set forth.

6. The combination, with the stem *a* and handle *b*, of hinged jaws *c c*, sliding sleeve *f*, and connecting-tongues *g g*, arranged and operating substantially as and for the purpose 65 set forth.

7. In a grasping or tongs device, substantially such as set forth, the combination, with the stem or handle, of the grasping jaw or jaws formed with slots *i i* and bar *k*, the tongue or rod *g*, having a hooked end engaging in said slot and bar, and a manipulating device 80 acting on said tongue to operate the jaw, substantially as herein set forth.

JOHN T. FOSTER.
